ABSTRACT: An array of tone signal sources is connectable to a common collector via key switches. The common collector leads to parallel percussive gating paths, normally nonconductive, which are turned on simultaneously in response to depression of any key regardless of the condition of other keys, and which become nonconductive gradually at diverse rates following the depression whether or not the key is released.

BANJO SIMULATION SYSTEM

BACKGROUND OF THE INVENTION

Musical interests exists in simulating percussive string instruments in electronic organs, without requiring skilled manipulation of keys to produce strumming effects. Percussive gates are well known, and it is known to produce musical effects responsive to plural then depressed keys of an organ, on depression of another key. The present system passes tone signal through parallel gates which are noncoincident in time, and which preferably carry tones of diverse tone colors. This simulates strumming. To simplify playing, a chord is percussively heard corresponding with all depressed keys, whenever even one key is depressed.

SUMMARY OF THE INVENTION

An organ arranged for simulating banjo tones by passing a called-for chord of tone signals through diversely timed percussive gates whenever one key of the organ is depressed.

BRIEF DESCRIPTION OF THE DRAWINGS

The single FIG. of the drawing is a schematic circuit diagram of a system according to the invention.

DETAILED DESCRIPTION OF THE PREFERRED EMBODIMENTS

10, 11, 12 represent a typical sequence of tone signal sources of an electronic organ. Typically they may be stages of a divider chain, providing square wave signals at frequencies of the equally tempered scale. A tone signal header 91 in which the sources 10, 11, 12 are connected, respectively, via key switches S_1' , S_2' , S_3' , and isolating resistances 15, 16, 17 to a common lead 18. The lead 18 diverges in two paths 19 and 20. In path 19 is included an emitter follower active filter 22 employing an NPN transistor T_4 , which supplies signal via a high pass filter 23 peaking at 1KC to the drain electrode of FET F_1 , the source electrode of which is connected via isolating resistance 24 to a terminal 25. Terminal 25 leads via a tab switch S_4 to an amplifier 26 and loudspeaker 27. Path 20 leads via high pass filter 30 to the drain electrode of FET F_2 , the source electrode of which is connected via isolating resistance 31 to terminal 25. Resistance 32 is connected from terminal 25 to ground, and represents a load across which voltage is developed for application to the input of amplifier 26.

When any keys are depressed, corresponding ones of switches S_1 , S_2 , S_3 are also closed, but switch S_1 and S_1' are commonly operated, as are S_2 , S_2' and S_3 , S_3' , etc. A DC header 90 in which voltage from terminal 40, at -100 v. is then applied, for each switch, via a separate large resistance ($1M$), typically 41 for the switch S_1 , 42 for the switch S_2 , and so on, which causes current to flow in resistances 43, 44, in series, the latter being connected to ground. The total current flowing in resistance 44, and therefore the total voltage thereacross, is a function of the number of switches S_1 , S_2 , S_3 ... which may be closed. Voltage transients across resistance 44 are transferred via capacitor 45 to the base of NPN transistor T_1 . The emitter of T_1 is grounded, and it is collector loaded by resistance 46. Its collector is capacitively coupled through capacitor 47 and a resistive divider network composed of resistances 48, 49, to the base of NPN transistor T_2 , which is emitter grounded and collector loaded by resistance 54. A direct connection 51 exists between the collector of T_1 and the base of T_2 , through resistance 52.

T_2 is normally nonconductive, which maintains T_1 conductive through feedback connection resistor 52. If T_1 becomes nonconductive in response to a negative signal, it turns T_2 on.

When a negative voltage arrives across resistance 44, on closure of one of switches S_1 , S_2 , etc., and this can occur regardless of whether or not others of the switches are then closed, a negative pulse is transmitted through capacitor 45, turning T_1 off. This action transfers a positive pulse to the base of T_2 , rendering it conductive. T_1 remains off as long as T_2 is

on, or conductive, because the collector of T_2 then provides a low resistance path to ground, so that the base of T_1 is essentially grounded. The design assures that if plural ones of switches S_1 , S_2 , etc., are closed almost, but not quite simultaneously, only one output pulse will nevertheless be derived from T_2 . This can occur due to imprecise playing.

When T_2 is turned on, a negative pulse is applied to the base of PNP transistor T_3 via capacitor 55, turning T_3 on momentarily.

10 T_3 is provided with collector voltage from terminal 56 via a voltage divider composed of resistances 57, 58, having a junction 59. This junction is normally negative, but when T_3 becomes conductive goes to nearly zero volts. A further voltage divider composed of resistances 60, 61 is connected between terminal 56 and ground, and provides a terminal 62. Terminal 62 is normally at -12 v. and terminal 59 at -18 v.

The voltage at terminal 62 is applied to the gate electrodes of FET's F_1 and F_2 , maintaining these nonconductive. The connections are made via resistances R_1 and R_2 , respectively, and timing capacitors C_1 and C_2 (.18 and .47), respectively, are connected between the gates and ground. The capacitors C_1 and C_2 are, then, normally charged to -12 v.

When T_3 is transiently turned on, the gates of F_1 and F_2 are 25 grounded via D_1 and D_2 through the collector of T_3 . This occurs substantially instantaneously. When T_3 reduces to cutoff condition, C_1 and C_2 charge towards -12 v. via R_1 and R_2 , respectively, i.e., audibly relatively slowly, and in due course F_1 and F_2 will turn off. This turnoff occurs with an exponential 30 characteristic. The time constant of R_2C_2 is about 2.5 times the time constant of R_1C_1 . The function of terminal 59 is solely to assure that D_1 , D_2 are biased off while T_3 is nonconductive, since there may be leakage current in T_3 , and the diodes D_1 , D_2 assure that capacitors C_1 , C_2 can discharge through a low 35 resistance circuit and charge through another high resistance circuit as T_3 turns on and off.

Filter 30 is a passive high pass filter, while amplifier 22 and associated components is an active high pass filter. Series capacitors 70, 71 act in series to discriminate against lows, and shunt capacitor 72 tends to bypass highs. T_4 is emitter loaded, and feeds back from the emitter via lead 73 to the base of T_4 via RC components R_4C_4 and C_5R_5 . These filters act to color tone, are per se well known, and other filters could well be substituted, so they have diverse characteristics suitable for the desired simulation of tone.

In operation, depression of one or more keys results in a transient turn-on of T_3 , which acts to rapidly turn on F_1 and F_2 , passing tone signal of two diverse colorations with instantaneous buildup. The struck tones then die away, but at different rates, so that one is sustained beyond the other by about 2.5 times. Specific values of R_1 , R_2 are selected according to the pinchoff characteristics of the FETs to provide a simulation of a banjo tone.

55 A percussive tone is sounded whenever a key is struck regardless of the length of time the key is held down, and if other keys are being held down when a key is struck, a percussive chord will be sounded in response to all the held down keys. It is within the scope of the invention to utilize more than two gates, if required to attain desired effects. To simulate a banjo, two gates are sufficient.

60 The time constant associated with F_1 is R_1C_1 . R_1 is selected so that when F_1 is triggered it will remain on for approximately 30 ms. The active filter associated with this gate is a high pass with a 12 db. peak at approximately 1 kc. The tone associated with this section tends to simulate the sound obtained from the drum head of the banjo when a string is plucked and is of short duration in nature.

65 The time constant associated with F_2 is R_2C_2 . R_2 is selected so that when F_2 is triggered it will remain on for approximately 75 ms. The passive filter C_3 , R_3 associated with this gate is a high pass filter but has no peaking. The tone associated with this section tends to simulate the sound obtained from the vibrating string. This portion of the tone is 2.5 times longer in duration than the tone associated with the drum head. These

relative values were derived by a listening test to determine which relationships best simulated the characteristic sound of a banjo.

I claim:

1. An electronic organ, comprising:
a source of tone signal;
a key switch connected in cascade with said source;
means responsive to closure of said key switch for generating a transient pulse;
a percussive gate connected to said key switch, said percussive gate having a gate electrode;
means normally applying a gating voltage to said gate electrode of magnitude and polarity adapted to maintain said gate nonconductive;
a capacitor connected between said gate electrode and a point of reference potential;
means responsive to said transient pulse for rapidly discharging said capacitor to said reference potential and thereafter for slowly charging said capacitor to said gating voltage;
said reference level being sufficiently low to render said gate conductive; and
an acoustic transducer connected in cascade with said gate.
2. The combination according to claim 1, wherein said percussive gate is a field effect transistor.
3. An electronic organ comprising:
plural sources of tone signals providing a gamut of tone signals arranged in frequency according to a musical scale;
a separate key switch connected in cascade with each of said sources;
a common collector connected in cascade with all said tone sources;
means responsive to closure of any of said key switches regardless of the then condition of the remainder of said key switches for generating a control pulse;
plural gates connected in parallel with each other to said common collector, said gates being normally nonconductive;
means responsive to said control pulse for rendering said gates rapidly conductive and thereafter relatively slowly conductive at audibly diverse rates for the separate gates; and
an acoustic transducer connected in cascade with said gates.
4. The combination according to claim 3, wherein is included a tone color filter in cascade with each of said gates, said tone color filters having diverse frequency response characteristics.
5. An electronic organ, including:
a source of tone signal;
a percussive gate connected with said source of tone signal;
a load for said gate, said gate including a gate electrode, a sustain capacitor connected between said gate electrode and a point of reference potential;
a source of off gating voltage;
a resistive circuit connected between said source of voltage and said gate electrode, said capacitor and resistive circuit having an audibly evident time constant;
a normally nonconductive switching transistor;
a normally nonconductive diode connecting said gate electrode to said transistor;
a source of control pulse connected in control relation to said switching transistor, said switching transistor arranged to be rendered conductive in response to said control pulse, said diode being poled to discharge said capacitor through said switching transistor while said switching transistor is conductive; and
an electroacoustic transducer connected to said gate.
6. The combination according to claim 5, wherein said switching transistor is a PNP transistor having a grounded emitter and a collector normally maintained at a voltage negatively greater than said gating voltage.

5

7. In a system for simulating banjo playing by means of an electronic musical instrument:

- means for generating steady state tone signals;
- means responsive to each of said tone signals for providing at least two tone signal components of audibly different frequency content;
- a control device;
- means including percussive gating circuits responsive to said control device for shaping said at least two tone signals to have substantially instantaneous and simultaneous buildups and relatively slow acoustically diverse decay rates immediately following the buildups, said decay rates differing by a factor of at least two; and
- an electroacoustic transducer responsive to the shaped tone signals, said frequency contents and decay rates being selected to simulate the sound of a banjo.

8. The combination according to claim 7, wherein said control device is a key switch and said electronic musical instrument is an electronic organ.

9. In a system for simulating playing tones by means of an electronic musical instrument:

- means for generating plural steady state tone signals;
- fingering devices for at will simultaneously connecting said tone signals to a common collector in response to selective actuation; and
- means responsive to actuation of any of said fingering devices regardless of the actuated condition of the remainder of said fingering devices for converting all the tone signals on said common collector corresponding with all the actuated fingering devices to plural percussive tones having substantially instantaneous rise times and respectively audibly diverse decay rates.

10. A tone generating system for an electronic organ, which simulates the sound of a single stroke of a banjo, comprising:

- a keyboard having an array of keys;
- means responsive to actuation of any one or more of said keys for calling forth corresponding tone signals and for generating a gate trigger voltage; and
- means in separate channels for filtering and shaping said tone signals to simulate in one of said channels a wave shape corresponding with the sound of the drum head of a banjo when strings are plucked, and in another of said channels the sound of said strings, said channels each including a separate percussive gate having a substantially instantaneous buildup and relatively slow decay times which are different by a factor of at least two for the separate percussive gates.

11. The combination according to claim 10, wherein the time constants for said decay rates are about 30 ms. for said one of said channels and about 75 ms. for said another of said channels.

12. The combination according to claim 11, wherein said means for filtering is a high pass filter for said one of said channels peaking at 1 kc. and is a high pass filter without peaking for said another of said filters.

13. In an electronic organ:

- a keyboard having keys;
- two distinct key switches closable in response to actuation of each of said keys;
- a separate tone source pertaining to each of said keys;
- a source of DC current common to all said keys;
- a DC header;
- a tone signal header;
- means responsive to actuation of any one of said keys for transferring tone signal from the tone source pertaining to that key to said tone signal header and said DC current to said DC header;
- plural tone signal channels connected in parallel to said one signal header, each of said tone signal channels including a separate tone forming filter and a normally nonconductive percussive gate;
- means responsive to each increase of current on said DC header for actuating all said gates to become highly con-

ductive substantially instantaneously and thereafter to effect decay of conductivity of said gates at widely diverse rates; and
the rates of decay and the characteristics of the tone forming filter being selected to produce a sound simulating the sound of a percussive stringed instrument. 5

14. In an electronic organ:
a keyboard having an array of keys, each pertaining to a musical tone signal, a header; means responsive to actuation of any one or combination of 10 said keys alone and simultaneously despite minor time separations among the actuations of the separate keys of the combination of said keys or the then actuated condition of others of said keys for generating only one control pulse, means responsive to actuation of any combination 15 of said keys for applying corresponding musical tone signals to said header while said keys remain actuated; means for applying said musical tone signals to said header distinctively via separate channels; and means responsive to said one control pulse for percussively shaping the tone signals in said separate channels in wave shapes which are different for the separate channels but identically independent in each of said channels of the durations of actuations of said keys. 20

15. In an electronic organ: 25
a common tone signal header;
a DC header;

an array of keys each pertaining to a tone signal source; key switches operable by said keys each for connecting one of said tone signal sources to said common tone signal header; a source of DC voltage; and means for further connecting said source of DC voltage to said DC header via a high resistance in response to actuation of each of said keys, whereby current in said header is a function of the number of said keys which are actuated, a DC load connected between said header and ground, a first transistor, a second transistor, means biasing said first transistor normally conductive and said second transistor normally nonconductive, means including a capacitive coupling network for only transiently coupling said first transistor to become transiently nonconductive responsive to predetermined voltage changes occurring across said DC load, means including a further capacitive coupling network for only transiently coupling said second transistor to become transiently conductive responsive to transient nonconductivity of said first transistor, at least one normally nonconductive tone gate responsive to the transient conductive condition of said second transistor to become initially conductive in a predetermined temporal pattern during said transient nonconductivity and thereafter, gradually resuming its nonconductivity. 30
